UNITED STATES PATENT OFFICE

FRANCIS J. DOWLING, OF NEW YORK, N. Y.

WHEELED CARRIER

Application filed April 13, 1929. Serial No. 354,783.

This invention relates to wheeled carriers. One object of the invention is to provide an improved device of the character described, that can be easily loaded, and conveniently dumped in the manner customary in wheelbarrows.

Another object of the invention is to provide a device of the nature set forth including a supporting frame having improved coaction with the trough of the device to permit the trough to move downward and tilt forward from the frame to constitute the front wall of the trough, an efficient lower digging wall of the same adjacent to the ground, in the upturned position of the device.

Another object of the invention is to provide a device of the character described including an improved scoop like fixture cooperating with the digging wall of the trough to increase the load that may be taken up by the device.

Another object of the invention is to furnish an improved device of the type mentioned comprising a supporting frame and a trough mounted thereon to pick up a load in the upturned position of the device, and the frame coacting to initially drive the trough into a pile of material on running the device along the ground.

A further object of the invention is the provision of a device of the class alluded to including improved means to facilitate the running of the device along the ground and into the pile of material that is to be dug.

A further object of the invention is to provide a device of the character described having improved means permitting the trough to be easily retracted on the frame with its load, and to be reliably seated on the frame in the retracted position thereof.

A further object of the invention is to furnish an improved device of the character described wherein the several movements of the trough or body with respect to the supporting frame therefor are properly guided and limited, and the return of the device to normal horizontal position and with the load properly received in the trough facilitated.

A still further object of the invention is to provide a device of the nature set forth which shall conform as far as possible to standard wheelbarrow construction, consist of comparatively few and simple parts, be inexpensive to manufacture, easy and rapid in operation and control, require ordinary manpower for its operation, and be reliable and efficient to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the several views.

In the drawings:

Figure 1 is a view of a manually wheeled carrier embodying the invention, and showing the same in normal substantially horizontal position.

Fig. 2 is a view in side elevation of the same in dumping position.

Fig. 3 is a bottom plan view of the device with portions of the handles removed.

Fig. 4 is a view of the same in upturned position and with the trough or body moved into spaced relation with respect to the supporting frame for digging.

Fig. 5 is a view of the device preparatory to breaking down on the handles to cause the body to receive its load.

Fig. 6 is a view of the device showing the frame returned to substantially horizontal position and depressed at the free ends of the handles to cause the body or trough to gravitationally return to normal position.

Fig. 7 is an enlarged vertical section taken on the line 7—7 of Fig. 1.

Fig. 8 is a vertical section taken on the line 8—8 of Fig. 7.

Fig. 9 is a view in vertical section taken on the line 9—9 of Fig. 1.

Fig. 10 is a sectional view taken through the trough and the scoop.

Fig. 11 is a vertical sectional view taken on the line 11—11 of Fig. 1.

Fig. 12 is a view in vertical section showing a catch.

Fig. 13 is a vertical sectional view showing a detail in the anti-friction means.

Fig. 14 is a sectional view taken on the line 14—14 of Fig. 3.

Fig. 15 is a view in side elevation of a modification of the invention showing the same in downward position.

Fig. 16 is an enlarged sectional view taken on the line 16—16 of Fig. 15.

This invention is an improvement over my application, Serial No. 259,178, filed March 5th, 1928.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, the invention provides a manually wheeled carrier, as, for example, a wheelbarrow having a main supporting frame, and a trough mounted thereon for movement therealong to dispose the front oblique wall of the trough as close as possible to the ground. For this purpose the said trough is movable in the upward position of the device downward and in forward tilting relation to said main frame. These movements can be accomplished by any suitable guide frame which forms a part of the main frame, and includes tracks, levers, links and other means well known in the mechanical arts, or as shown, by a combined slotted and pivoted arrangement, the pivot constituting a follower movable along the guide slot. Further, the trough has members having guiding coaction with the main frame to eliminate any tendency to lateral movement of the trough with respect to the frame. Any suitable locking or securing means serves to hold the trough against movement on the main frame from the normal position. On release of the locking means, and upturning of the device, the trough moves easily forward on the carriage, and is easily permitted to swing away therefrom. With the guide frame now extending substantially vertical, the handles extend at a convenient inclination to permit the device to be easily driven along the ground and strongly into a pile of material. The said handles act against the trough substantially at the said digging wall thereof and retain the body and guide frame in stable relation to prevent collapse of the device while thus

manipulated. Anti-friction means may operate with the frame and the trough to permit the device to be easily run along the ground in the upturned position mentioned. After the initial movement into the pile has been completed, the handle means is disengaged, and the same brought up and locked with the guide frame. Then the operator pulls the handles toward himself to return the handles to the ground to tilt the body upward to uniformly receive the load. Then the trough is retracted by the operator grasping the rear wall thereof, the trough riding easily rearward on an anti-friction device, and seating uniformly along its entire length on the frame of the carrier. A scoop may be used, if desired to coat with the front digging wall of the trough to increase the quantity of material that may be picked up by the device, the said scoop being movable out of this position to permit dumping of the load.

Within the scope of the invention, the several members constituting the guide frame may be embodied in a simple rectangular frame consisting of a uniform L or T section, the trough having guiding and swiveled engagement with the parallel flanges of the guide frame, and the latter being connected at its front end to the axle of the wheel. While the guide frame is shown pivoted to the handles at the axle of the wheel, this pivotal engagement may be provided at any other suitable point, as for instance, at the toe of the main frame. The pivotal mounting for the trough may then be omitted, and the trough merely slide along the guide frame. The trough may be considered as being pivotally mounted on the main frame itself. While the wheel is shown as being mounted on both the guide frame and the handles, it may be mounted on but either one of them alone. Any other wheels, auxiliary to the main wheel, may also be employed on the frame.

Although the invention is shown as embodied in a wheelbarrow, it will be understood that the same is applicable to wheeled carriers of various types.

Referring in detail to the drawing, 20 denotes a device embodying the invention. The same includes a trough 21 that is mounted upon a main frame 22. The latter is supported to be readily moved along the ground by any suitable number of wheels, preferably one, which is shown at 23. Co-operating with the wheel 23 is an underbrace or rest 24 that is utilized when the device is resting in stationary normal position on the ground.

The trough 21 is mounted on the frame in any suitable relation thereto, preferably in the conventional manner practised in wheelbarrows so that the device can be readily moved along the ground by an operator holding the handles 25 at their rear free ends 26. Furthermore, the trough 21 is retained as

closely to the main frame 22 as possible so that the device can be easily dumped when upturned into vertical position on the front brace or toe 27. The trough 21 is also of well known or standard construction having a bottom 28, sides 29, and front and rear walls 30 and 31, respectively. The said trough is constructed of any suitable material, as for example, metal, and is braced in any required manner to withstand all the strains to which it may be subjected. The structural bracing that might be provided for the trough may assume many different forms and it has therefore been preferred not to disclose the same herein. At any rate, it will be noted that the front wall 30 forms a comparatively large oblique angle with the bottom so that the entire contents of the trough may be easily dumped and caused to slide off the front wall 30 in the position shown in Fig. 2.

The main frame 22 includes a guide frame 32 that is relatively movable with respect thereto. The said guide frame is pivotally supported at its front end directly on the axle 33 of the wheel, and at its rear end on the handles 25. The latter extend at a suitable angle with respect to each other as shown in Fig. 3 in a manner well known in wheelbarrows, and the front ends of the handles 25 are suitably anchored together by means of a cross or toe brace 34. The underbraces 24 are secured to the handles 25 and may be re-enforced by any suitable cross members as shown at 35. Any additional cross bracing can be provided for the handles 25, as, for example, by means of a bar 36 that extends along the underside of the handles and has upwardly directed end flanges 37. At the front ends of the handles are a pair of locking abutments 38. The latter coact with and may form a part of the toe piece 34. In the embodiment of the invention shown the devices 38 comprise arcuate bars 39 that are secured to the handles and extend forward thereof and terminate in the transverse pins 40. The bars 39 can be made of any required length, and may be no longer than the toe piece 34 itself.

The guide frame 32 comprises a pair of parallel guide means along which the trough is slidable, said guide means being pivotally mounted on the axle 33, and the trough being movable along the guide means downwardly with respect thereto in the upturned position of the device, and with the said trough, furthermore, tilted away from the frame in a forward direction. This forward tilting motion of the trough is not absolutely essential, and may be omitted inasmuch as the guide frame 32 may assume the required inclination about the pivot 33 so that the trough may extend always at a fixed relation or angle to the guide frame, and nevertheless override the wheel 23 and also

lie with the front wall 30 in comparatively close proximity to the ground.

The guide frame 32 may include a plurality of bars 41 that are made of any suitable material as, for example, wood. Their front ends 42 terminate approximately at the axle 33 to which they are connected by means of any suitable bearings 43 which may be like the bearings 44 on the handles 25. The bars 41 are cross braced in any desired manner, as, for example, by means of a pair of parallel metal bars 45 which are interconnected by means of straps 46. The bars 41 lie within the handles 25 and in relatively close proximity thereto and preferably follow the inclination of the handles, although within the scope of the invention, the bars 41 may also be parallel to one another. Included in the guide frame 32 are a pair of guide members 47 that are secured to the bars 41. The guide members 47 are parallel to each other, and accordingly in the construction shown, form an angle with the bars 41. While the guide members 47 may be embodied in the different forms, as, for example, in structural sections, which may also include the bars 41 as an integral part thereof, I have shown them herein as being in the nature of flat metal plates which are connected to the bars 41 in any well known manner by means of angle clips or straps or the like. Also the plates 47 may be secured to the braces 45 and 46. It will be noted that in the normal position of the device, the bars 41 are disposed between the planes defined by the handles 25 as clearly shown in Figs. 1 and 2. The plates 47 are of minimum width above their supporting bars so that the trough will be kept down as close as possible to the main frame. In order to adhere as closely as possible to standard wheelbarrow construction, the plates 47 are wider at their front ends and taper down toward their rear ends, thus corresponding to the wooden wedges that are well known in wheelbarrow construction.

In order to facilitate the movement of the trough downward along the guide frame 32, the plates 47 are slotted lengthwise as shown at 48, and the trough provided with any suitable means to engage within the slots. As one means of accomplishing this purpose, a plurality of angles 49 are extended along the bottom of the trough in parallel relation to one another. The horizontal flanges are secured to the bottom of the trough, while their vertical flanges lie preferably along the inside faces of the plates 47 in easy sliding contact therewith. Secured to the angle bars 49 at the ends thereof is a pivot bar 50, the end portions of which are slidable along the slots 48 with the bottom of the trough in spaced relation to the plate 47. The rear ends of the slots 48 are recessed at 51 toward the bars 41 to receive the pivot bar 50 and permit the trough to drop down with the

bottom thereof seating directly on the plates 47. Thus the pivot bar 50 acts as an anti-friction means that permits the trough to be easily retracted with its load. While the reaction occurs, the bottom of the trough will not contact the plates 47. When fully retracted, however, the trough reliably seats on the plates 47 and relieves the pivot bar 50 of all strains due to the weight of the trough and its load, while the wheeled carrier is in normal, horizontal position. Spanning across between the plates 47 is a roller bar 52 that is journaled in the plates and is so positioned that the vertical flanges of the angle members 49 are adapted to ride thereon, as, for example, in the position of the device shown in Fig. 6.

In order to limit the maximum angle that the guide frame may make with the handles 25, any suitable stop means variously positioned can be used, as, for example, the angle pieces 53 that are mounted on the handles 25 and are adapted to abut the bars 41.

25 The members 49 have recesses 54 formed therein to receive the pins 40, whereby a strong abutment engagement is effected between the trough and the handles 25 for strong forward actuation of the trough into 30 the pile of material to be dug. These recesses 54 are of such form that the pins 40 may be readily received and released therefrom. Due to the coaction of the stop 53 with the pivot bar at the lower ends of the slots 48 in 35 Fig. 4, the pins 40 may be readily engaged within the recesses 54 without the slightest difficulty. Brackets 54a prevent the roller bar catching in the recesses.

In order to retain the guide frame 32 in 40 normal engagement between the handles 25, the flanges 37 are formed with L-shaped slots 55 above the plane of the handles 25. Disposed within the slots 55 and extending across from handle to handle is a bar 56 which is 45 adapted to take over the free rear ends 57 of the guide frame 32. In order to release the guide frame 32, the locking bar 56 is moved in a rearward direction to the toe of the L-slot, thus permitting the ends 57 to clear the said bar. However, when it is desired to engage 50 the handles and the guide frame together, the locking bar 56 is brought over the ends 57 into the part of the L-slot remote from the toe as clearly shown in Figs. 1 and 2.

55 In order to lock the trough to the guide frame, links 58 are connected to the pivot bar 50, these links being positioned inside of the members 49. Extending through the other ends of the links is a rod 59 securely attached.

60 The plates 47 include portions 60 that are notched at 61 on their underside edges. The links 58 together with the rod 59 are swingable about the bar 50 as a pivot into the position shown in dotted lines in Fig. 2 and with 65 the said bar seating in the notches 61. Since

the pivot bar 50 is strongly secured to the structural members 49 of the trough, the latter is thereby held against downward movement with respect to the guide frame 32. In order to break the strain that would be 70 caused by the weight of the body and its contents, as, for example, in dumping position, upon the links 58, the pivot bar 50 seats in the recesses 51 in which the pivot bar is reliably retained by the co-operating links 58 and the 75 rod 59. To permit the trough to ride downward along the guide frame, the links 58 are thrown upward into the position shown in Fig. 4, and with the rod 59 riding along the edges 62 of the plates 47, if desired.

In order to hold the front end portion of the trough reliably on the guide frame, hooks 63 are secured to the members 49 or to any other convenient portion of the structure, the hooks being so directed as to receive the roller 85 bar 52 when the trough is returned to its position on the guide frame as shown in Fig. 2. This locking arrangement acts automatically both for engagement and release, according as the trough moves into one or another 90 position.

If it be desired to afford lateral support to the trough to facilitate the return thereof to normal position as shown in Fig. 6, there may be provided on the underside thereof a channel 65 that extends centrally longitudinally along the bottom of the trough substantially the entire length thereof and flares downward as clearly shown in Fig. 9 to readily receive and engage the peripheral portion of the wheel 23. The latter provides a rolling support for the trough in the position of the device above mentioned.

If the frictional resistance of the digging wall 30 of the trough with the ground be a factor in the operation thereof, a plurality of rollers 66 or other anti-friction means can be arranged to suitably space the said wall from the ground. The said rollers are preferably set into openings 66a formed in the front wall 30, which openings are closed in any suitable manner, as, for instance, by means of casings 67 that extend into the trough and are properly connected to the wall thereof, the axles for the rollers being journaled in any suitable manner in the side walls of the said casings. In order to increase, if that be necessary, the size of the load that may be dug by the trough, a scoop 68 may be mounted on the trough, the use of which may be rendered optional, depending upon the operations in which the wheelbarrow is employed, the material that is to be dug, and also upon the skill of the operator. This scoop 68 is pivotally mounted on the trough at 69 by means of any suitable brackets, as, for example, those shown at 70. The pivotal mounting at 69 may be rendered detachable if found most convenient. The scoop 68 includes the side wall portions 75

and a front or digging wall portion 72 which in the position shown in Fig. 4, lie within the trough and with the wall 72 constituting a straight forward extension of the wall 30 of the trough. The wall 72 will afford possibilities of digging a very large load and also of retaining it suitably within the trough when the wheelbarrow is being moved along from place to place. In order to dump the contents of the trough, the scoop 68 is moved rearward of the body and into the position shown in Fig. 2, so that the front wall 30 of the trough is free of even the slightest obstruction and is nevertheless at a sufficient height above the ground so that the contents of the wheelbarrow can be easily dumped. This rearward position of the scoop may be used when moving the wheelbarrow around from place to place, or it may be kept in the forward position, whichever may be found most convenient or desirable. If the side walls 29 of the trough extend at an inclination toward each other, the scoop may, in the rearward position, lie along the outside 25 of the end of the trough. In the dumping position, the scoop may be either gravitationally retained in its rearward position, or it may be locked there.

The operation of the device will now be clearly apparent. The wheelbarrow being in horizontal position on the ground, the locking members 56 and 59 are released, permitting the trough to be pushed forward along the guide frame 32, over the wheel, whereupon, on upturning the main frame, the guide frame and the handles are readily separated angularly. The former is in substantially vertical position or inclined slightly toward the rear from the axle 33, while the handles 25 extend rearward at a suitable angle so that the ends 26 thereof are at a proper height above the ground to be conveniently manipulated by the operator. The pins 40 engage in the recesses 54 in the members 49, this being facilitated by the coaction of the stops 53 which limit the angle as between the guide frame and the handles 25. A slight downward pressure may be exerted on the ends of the handles to bring the pivot bar 50 strongly into the lower ends of the slots 48, and even if necessary, to slightly raise the trough so that the pins 40 will instantaneously snap into their recesses. The scoop 68 may have been previously thrown into the forward digging position. Now the operator, acting on the handles at a slight run, drives the device strongly into a pile of material. Thereafter the handles 25 are brought into substantially upright position into the plane of the bars 41 of the guide frame. By doing this rapidly, the locking bar 56 will automatically be thrown from the toe end of the L-slot 55 forward and downward along the slot to engage over the ends 57 of the guide frame, thereby

locking the latter to the handles. The device is now in the position shown in Fig. 5. It will be noted that the wheel 23 may have been previously moved against the bottom of the trough and into the channel 65. If, however, the arms 39 were made shorter, the wheel 23 would always be in direct engagement with the bottom of the trough, although that might necessitate that the slot 48 be slightly lengthened. Now the operator breaks down 70 on the handles to return the frame to substantially horizontal position and may continue bearing down on the ends 26 of the handles to raise the front end of the device and cause the trough to ride rearward over the wheel 23 and the roller 52. It will be appreciated that when this occurs, the bottom of the trough clears the edges 62 of the plates 47 so that frictional resistance is minimized. When the trough reaches its rear normal position, the hooks 63 engage the guide roller automatically and at the same time the pivot bar 50 drops into the recesses 51 and the links 58 fall gravitationally and automatically engage with the rod 59 in the notches 61 as shown in Fig. 2. Since the members 49 are beveled at their front ends as shown, these will also clear the roller 52, thereby permitting the bottom of the trough to directly rest on the edges 62 of the plates 47. The scoop 68 may now be thrown rearward and the device can be run along the ground from place to place. In order to dump the contents of the trough it is merely necessary to upturn the device by raising the ends of the handles, the movement in this respect being entirely similar to that which is practised in any conventional wheelbarrow.

The movement shown in Fig. 6 can be dispensed with, and the trough merely manually retracted by grasping the rear wall thereof.

In Figs. 15 and 16 is shown a modification of the invention wherein the pivotal movement of the body with respect to the guide frame is eliminated. This may be accomplished in part by providing a guide frame 75 that is pivotally mounted at 76 in proximity to the extreme forward end or toe of the handle frame 77. The latter has the usual wheel 78 mounted thereon at 79 and an underbrace 80 to cooperate with the wheel. The locking device 37, shown more particularly hereinbefore, is mounted on the handles to function in a similar manner.

The guide frame 75 may consist of structural sections such as angle members 81 which are individually pivoted to the handle 77 at 76. The trough 82 has any suitable guide members 83 to engage adjacent flanges of the angle members. In order to cause the handle 77 to strongly act against the trough in driving the same forward into a pile, stop elements 84 are secured to the underside of the trough in position to be engaged by the forward ends of the handles. These stop ele-

ments may be secured to a guide means 85 that peripherally engages the wheel 78 in a manner similar to member 65 hereinbefore described. While the angle members 75 may be disposed at their forward ends along the outside of the handles 77, yet they are adapted to be received at their rear ends between the said handles, it being understood that the members 75 extend in parallelism to each other. When thus received between the handle 77, the locking device 37 will readily function as aforesaid. The portions 86 at which the angle members are pivotally mounted may consist of projections or extensions that may be secured in any suitable manner to the said members. At the rear end of the body is a latch in the form of one or more hooks 87 that are adapted to automatically snap into engagement with the ends of the angle members 75 or with a cross brace that may be provided to connect the ends of the angle member together.

In operation, the trough 82 is positioned initially in a manner similar to that in Fig. 1. On release of the latching device 37 the guide frame 75 moves upward about the pivot 76 and simultaneously the latch 87 may be released, causing the trough 82 to move downward and thus serving to automatically accomplish the pivotal movement of the guide frame. The ends 77a of the handle 77 will now automatically engage the stops 84 so that the trough can be readily driven into a pile. The latch 87 may in this position merely ride freely over the guide frame. Thereafter the handles 77 are moved forwardly about the pivot 79 of the wheel and secured with the guide frame by the locking device 37. On breaking down on the handles 77, the trough 82 moves rearwardly and readily rides over the wheel 78. It will be clearly apparent that the stops 84 are now out of engagement with the ends 77a of the handles. On reaching its extreme rearward position, the latch 87 automatically engages the rear end of the guide frame to lock the trough. In order to dump the contents of the trough, the device is upturned in the usual manner and rests upon the front end 77a of the handles.

The slope of the front digging wall can in any case be varied to suit, and may be made much larger than that shown, and approximate an angle of 40° with the plane of the bottom of the trough. The bottom of the trough may be shortened, when so increasing the slope of the digging wall. The scoop may be omitted, and substantially a full load nevertheless dug and loaded.

From the foregoing, it will be seen that there is provided a device which achieves the objects of this invention and accomplishes advantages of practical value. The body of the wheeled carrier is positioned on the carriage so as to be always ready for immediate

use, whether it is desire of the operator to load or dump the device.

Many embodiments may be made of the above invention, and many changes may be made in the embodiment above set forth. It is to be understood that all matter hereinbefore set forth, or shown in the accompanying drawing is to be interpreted as illustrative and not in a limiting sense.

It will be understood that such terms as front, rear, up, and derivatives and combinations therefrom are used herein in an approximate, relative, and illustrative sense to clearly define the invention, and not to limit the principles thereof.

I claim:

1. A device of the character described, including a wheeled carrier comprising a frame having wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed.

2. A device of the character described, including a wheeled carrier comprising a frame having wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed, said frame being carried by the wheel means in the digging position of the device.

3. A device of the character described, including a wheeled carrier comprising a frame having wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device,

to cause the front wall of the trough to lie along the ground and in proximity thereto, the said frame being actuated as aforesaid to drive the said front wall strongly into a pile, and means to retain the trough in the digging position till the digging has been completed, said frame being carried by the wheel means in the digging position of the device, said frame being downwardly actuated after digging to raise the trough and return the device to initial position with the trough riding rearward over the said wheel means.

4. A device of the character described, including a wheeled carrier comprising a frame having wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed, the said frame being movable upward to the guide means to engage the latter and permit breaking down on the frame at the rear end thereof.

5. A device of the character described, including a wheeled carrier comprising a frame having wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed, the said frame being movable upward to the guide means to engage the latter and permit breaking down on the frame at the rear end thereof, the frame having an underbrace rearward of the wheel, about which underbrace the frame can be tilted to raise the forward end thereof and cause the trough to gravitationally move rearward to initial position on the guide means.

6. A device of the character described, including a wheeled carrier comprising a frame having wheel means at the front end thereof, said frame being actuated at its rear

end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed, the said frame being movable upward to the guide means to engage the latter and permit breaking down on the frame at the rear end thereof, the frame having an underbrace rearward of the wheel, about which underbrace the frame can be tilted to raise the forward end thereof and cause the trough to gravitationally move rearward to initial position on the guide means, and means to automatically lock the trough to the guide means against movement, coincident with the return of the trough.

7. A device of the character described, including a wheeled carrier comprising a frame having a wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed, the said frame being movable upward to the guide means, and other means to automatically lock the frame to the guide means on completion of such movement.

8. A device of the character described, including a wheeled carrier comprising a frame having a wheel means at the front end thereof, said frame being actuated at its rear end, said frame including guide means mounted in proximity to the front end thereof, said guide means lying normally along the frame and being movable upward with respect thereto, a trough on the frame coacting for movement along the guide means in a downward direction in the upturned position of the device, to cause the front wall of the trough to lie along the ground and in proximity thereto, the said frame being actuated as aforesaid to drive the said front wall strongly into a pile, and means to retain the trough in the digging position till the digging has been completed, the said frame being movable upward to the guide means, and other means to automatically lock the frame to the guide means on completion of such movement.

trough in the digging position till the digging has been completed, the said frame being movable upward to the guide means to engage the latter, and permit the breaking down 5 on the frame at the rear end thereof, the trough retaining means being automatically disengaged on the upward movement of the frame.

9. A device of the character described, including a wheeled carrier comprising a frame having a wheel means at the front end thereof, said frame being actuated at its rear end, said frame including guide means mounted in proximity to the front end thereof, said 10 guide means lying normally along the frame and being movable upward with respect thereto, a trough on the frame coacting for movement along the guide means in a downward direction in the upturned position of 15 the device, to cause the front wall of the trough to lie along the ground and in proximity thereto, the said frame being actuated as aforesaid to drive the said front wall strongly into a pile, and means to retain the 20 trough in the digging position till the digging has been completed, said trough having pivotal engagement at its rear end with the guide means to move forward from the same.

30 10. A device of the character described, including a manually wheeled carrier comprising a frame having a wheel adjacent to the front end thereof, said frame being adapted to be manually operated at its rear end, and 35 means including a trough mounted on the frame for downward movement of the trough substantially parallel to the frame and forward tilting of the trough with respect to the frame in the upturned position of the carrier.

11. A device of the character described, including a manually wheeled carrier comprising a frame having a wheel means adjacent the front end thereof, said frame being adapted to be manually operated at its rear end, a trough on the frame, said trough having a front oblique digging wall, means mounting said trough for forward tilting movement with respect to the frame in the upturned position of the carrier to cause the digging wall to approach a condition of approximate parallelism to the ground, and other means to releasably retain the trough in the digging position.

55 12. A device of the character described, including a carrier comprising an approximately horizontal wheeled frame and a trough thereon, said frame being manually manipulated at the rear end thereof, and means pivotally mounted on the frame at the front end thereof, said means being forwardly movable at an angle with the frame in the upturned position of the latter, the trough 60 being downwardly movable along said means,

said frame coacting against the bottom of the trough in the upturned position mentioned, driving the trough into a pile, and coacting with the trough to cause the same to take up its load, on returning the frame 70 to initial position.

13. A carrier including a frame having a wheel means adjacent to the front end thereof and manually manipulated at the rear end thereof, said frame being approximately 75 horizontal, a trough on the frame, said trough having an oblique front digging wall, movable means on the frame providing pivotal coaction and forward movement of the trough, with respect to the frame for 80 movement with the front end of the trough spaced from the frame, whereby the front digging wall approaches a position of approximate parallelism to the ground and in 85 relatively close proximity thereto, said frame coacting with said means to be forwardly swingable to engage the trough to elevate the same from the ground in swinging the frame back to initial position.

14. A carrier including a frame having a 90 wheel means adjacent to the front end thereof and manually manipulated at the rear end thereof, said frame being approximately horizontal, a trough on the frame, said trough having an oblique front digging wall, movable means on the frame providing pivotal coaction and forward movement of the trough with respect to the frame and with the front end of the trough spaced from the frame, whereby, in the upturned position of the carrier, the said front digging wall approaches a position of approximate parallelism to the ground and in relatively close proximity thereto, said frame being movable 100 into bearing relation with the bottom of the trough to elevate the trough from the ground in swinging the frame back to initial position, and means acting between the trough and the frame in the upturned position mentioned to retain the trough in digging relation to the frame, said means being disengageable to permit the trough to be moved rearward along the frame and returned to initial position thereon.

110 15. A carrier including a frame having a wheel adjacent to the front end thereof and manually manipulated at the rear end thereof, said frame being approximately horizontal, and a trough on the frame, said trough having an oblique front digging wall, and means having pivotal engagement with the frame to move angularly forward with respect thereto, the trough being downwardly movable along the said means, whereby, in 115 the upturned position of the carrier, the said front digging wall approaches a position of approximate parallelism to the ground and in relatively close proximity thereto, said frame in the upturned position coacting with 120 125 130

- the trough to elevate the same from the ground in swinging the frame back to initial position, and means acting between the trough and the frame in the upturned position mentioned to retain the trough in the said digging relation to the frame, said means being disengageable to permit the trough to be returned to normal position on the frame, and anti-friction means, other than the wheel, coacting between the carrier and the ground in the upturned position to permit the carrier to be run along the ground. 5
16. A carrier including a frame having a wheel adjacent to the front end thereof and manually manipulated at the rear end thereof, said frame being approximately horizontal, and means on the frame supporting the trough for forward movement therealong, said trough having an oblique front digging 15 wall, said means having pivotal engagement with the frame to swing frontward and bring the front end of the trough in front of the wheel, whereby, in the pivotally upturned position of the trough, the said front digging 20 wall approaches a position of approximate parallelism to the ground and in relatively close proximity thereto, means to releasably lock the trough in digging position with the frame, and the frame including means extending rearward of the trough to cause the said digging wall to be driven into a pile. 25
17. A carrier including a frame having a wheel means adjacent to the front end thereof and manually manipulated at the rear end 30 thereof, said frame being approximately horizontal, and a trough on the frame, said trough having an oblique front digging wall, and means providing movable pivotal engagement between the trough and the frame 35 whereby the trough is movable frontward along the frame and with the front end of the trough in front of the wheel, so that in the upturned position of the carrier, the said front digging wall approaches a position of 40 approximate parallelism to the ground and in relatively close proximity thereto, and other means engageable between the frame and the trough to provide a triangle of forces between said frame, said trough and said 45 first mentioned means for digging actuation of the trough for driving the said digging wall strongly into a pile. 50
18. A carrier including a frame having a wheel adjacent to the front end thereof, said frame extending along the ground and being manually actuated at its rear end, and a trough mounted on the frame to move with its forward end into spaced relation to the 55 frame in the upturned position of the latter. 60
19. A carrier including a frame having a wheel adjacent to the front end thereof, said frame extending along the ground and being manually actuated at its rear end, and a trough mounted on the frame to move with 65 its forward end into spaced relation to the frame in the upturned position of the latter, and means to releasably engage the trough against the movement mentioned. 70
20. A carrier including a frame having a wheel in proximity to the front end thereof, said frame extending along the ground and being manually actuated at its rear end, and a trough mounted on the frame to move with its forward end away from and into spaced relation to the frame, said frame including means extending rearward with respect to the trough to cause the frame to act on forward end of the trough to drive the trough 75 strongly into a pile. 80
21. A carrier including a frame having a wheel at the front end thereof, said frame extending in proximity to a comparatively small angle with the horizontal and being manually manipulated at the rear end thereof, a trough on the frame, said trough having a front digging wall, and a movable scoop coacting with said digging wall to provide an extended digging area. 85
22. A carrier including a frame having a wheel at the front end thereof, said frame extending at a comparatively small angle with the horizontal and being manually manipulated at the rear end thereof, a trough on the frame, said trough having a front digging wall, and a movable scoop coacting with said digging wall to provide an extended digging area, said scoop being movable to the rear end of the trough to permit the load in the latter to be dumped. 90
23. A device of the character described, including a carrier comprising an approximately horizontal wheeled frame manually manipulated from the rear end thereof, a trough on the frame having an oblique front digging wall, and means acting between the trough and the frame to cause said trough to be movable in the upturned position of the frame downward and in forward swinging relation to said frame to bring said digging wall to approach a position of approximate parallelism and in close proximity to the ground, said frame being engageable with the trough in the upturned position thereof to cause the latter to be manually rearwardly swung from the upper end thereof back to initial position, and a scoop coacting with said digging wall to provide an extended digging area, said scoop being movable away from said digging wall to permit dumping of the load in the trough. 95
24. A carrier including a frame having a wheel at the front end thereof, said frame extending adjacent to a comparatively small angle with the horizontal and being manually manipulated at the rear end thereof, a trough on the frame, guide means for the trough, said trough seating on the frame and being 100 slideable frontward with respect thereto, and 105

anti-friction means spacing the trough from the frame, said anti-friction means coacting between the guide means and the trough in the sliding movement of the latter.

25. A carrier including a frame having a wheel adjacent to the front end thereof, said frame extending at a comparatively small angle with the horizontal and being manually manipulated at the rear end thereof, a trough on the frame, and means mounting said trough on the frame for movement with the front end thereof in spaced relation to the frame in the upturned position of the trough, means to retain the trough in the spaced relation mentioned during the digging, and other means extending rearward from the frame and coacting with the first mentioned means to cause the frame to drive the trough strongly into a pile.

26. A carrier including a frame, having a wheel adjacent to the front end thereof, said frame extending rearward from the wheel in approximately horizontal position, a trough on the frame movable forward over the wheel, and retractable rearward back to normal position, guide means for the trough, and anti-friction means between the trough and the guide means, said anti-friction means being movable out of load-carrying coaction when the trough is fully retracted, to permit the trough to seat on the guide means.

27. A device of the character described, including a wheeled carrier comprising a frame having a wheel means near the front end thereof and adapted to be manually operated from the rear thereof, a trough on the frame having an oblique front digging wall, and forward movable means on the frame swingably mounting said trough for forward and tilting movement into frontward relation with relation to the adjacent end of the frame to permit the said digging wall to approach a condition of approximate parallelism to the ground.

28. A device of the character described, including a carrier comprising an approximately horizontal wheeled frame including handles manually manipulated at the rear end of the frame, and a trough on the frame having an oblique front digging wall, said trough being movable in the upturned position of the frame downward and in forward swinging relation to said frame to bring said digging wall to approach a position of approximate parallelism with and in close proximity to the ground, said frame being rearwardly swingable with respect to the trough for releasable abutment with the bottom of the trough to drive the trough into a pile, the frame being further rearwardly swingable from the handles back to initial position in engagement with the trough to cause the same to take up its load.

29. A carrier including a frame having a wheel means adjacent to the front end there-

of and manually manipulated at the rear end thereof, said frame being approximately horizontal and having a guide means, and a trough on the frame, said trough having an oblique front digging wall, said means providing longitudinally movable pivotal engagement between the frame and the trough for movement of the latter forward with respect to the frame and with the front end of the trough forward of the frame, whereby the said front digging wall approaches a position of approximate parallelism to the ground and in relatively close proximity thereto, the frame being positioned to be carried by the wheel means in the digging position of the trough.

30. A wheeled device of the character described, including a carrier comprising an approximately horizontal means manipulated from the rear end thereof, and a trough on the means having an oblique front digging wall, said trough being movable in the upturned position of the means downward and in forward swinging relation to said means to bring said digging wall to approach a position of approximate parallelism and in close proximity to the ground, said means being swingable forward in the upturned position thereof preparatory to being manually rearwardly swung from the upper end thereof back to initial position, and a frame supporting the said means and extending along the said means in the initial position of the latter, said frame being pivotally engaged with the said means for movement with the end portions thereof extending rearward and forward of the said means in the upturned position of the latter, the forward end of the said frame detachably engaging the bottom of the trough, and the rearward end of the frame being manually actuated to drive the trough into the pile, the said frame being forwardly swingable to lie along and engage the upper end of the said means in the upturned position of the latter for causing the trough to take up its load.

31. A carrier including a frame having a wheel means adjacent to the front end thereof, said frame extending rearward from the wheel approximately horizontally, engagement means including guide means on the frame, a trough on the frame movable forward therewith by said means over the wheel, said frame in the upturned position of the trough engaging the same for driving the trough with the front wall thereof strongly into a pile for digging, said frame being movable for coaction with the engagement means for breaking down by pressure on the rear end of the trough to fill the load into the same, said trough being mounted for retraction along the guide means and the frame in the rearward direction into normal position, and anti-friction means between the trough and the said means to permit easy retraction of

the trough with the latter in spaced relation to the frame, said means in the retracted position of the trough permitting the latter to seat directly on the frame and in frictional engagement therewith.

5 In testimony whereof I affix my signature.

FRANCIS J. DOWLING.
